DESIGN FOR WRAPPING PAPER

James V. Di Yorio, Denver, Colo., assignor to The Denver Wholesale Florists Company, Denver,
Colo., a corporation of Colorado

Application February 24, 1948, Serial No. 144,710

Term of patent 14 years

(Cl. D59—2)

To all whom it may concern:

Be it known that I, James V. Di Yorio, a citizen of the United States of America, residing at the city and county of Denver, State of Colorado, have invented a new, original, and ornamental Design for Wrapping Paper, of which the following is a specification, reference being had to the accompanying drawing, forming part thereof.

The figure is a face view of a piece of wrapping paper, showing my new design. The dotted lines indicate a design unit which repeats vertically on the drawing.

The essential features of my design reside in the portions shown in full lines.

I claim:

The ornamental design for wrapping paper, substantially as shown and described.

JAMES V. DI YORIO.
